Electric Company, a corporation of New York

Filed Apr. 30, 1962, Ser. No. 69,899

Term of patent 14 years

(Cl. D56—4)

FIG. I.

FIG.2.

FIG.3.

FIG.4.

FIG.5.

FIG.6.

FIG. 1 is a top perspective view showing my new design of a portable phonograph, with the cover in an open position;

FIG. 2 is a reduced right side elevational view with the cover in a closed position;

FIG. 3 is a reduced top plan view thereof;

FIG. 4 is a reduced left side elevational view;

FIG. 5 is a reduced front elevational view; and

FIG. 6 is a reduced rear elevational view.

The bottom of the phonograph is substantially the same as the top in FIG. 3 except for the provision of a plurality of bumper feet thereon, as shown in FIGS. 2, 4, 5 and 6.

I claim:

The ornamental design for a portable phonograph or similar article, substantially as shown and described.
